DESIGN FOR A RULER

William J. Turner, Northport, N. Y.

Application November 3, 1942, Serial No. 108,689

Term of patent 7 years

To all whom it may concern:

Be it known that I, William J. Turner, a citizen of the United States, residing at Northport, County of Suffolk, State of New York, have invented a new, original, and ornamental Design for a Ruler, of which the following is a specification, reference being had to the accompanying drawing, forming part thereof.

The figure is a plan view of a ruler, showing my new design.

My ruler is of conventional thickness.

I claim:

The ornamental design for a ruler, as shown and described.

WILLIAM J. TURNER.
